(57) **ABSTRACT**

A stretcher apparatus for transporting a patient while keeping the patient warm includes a flexible shell with an insulating layer and handles distributed along a perimeter of the shell. The shell may receive the patient into an interior space enclosed by the shell so that the patient may be carried by lifting via the handles. The insulating layer keeps the patient warm during transport.

FIG. 1

FIG. 2

FIG. 3

FIG. 4

FIG. 5

FIG. 7

The plurality of handles 40 is distributed around the perimeter wall 18 of the shell 12. Each handle 40 of the plurality of handles 40 comprises a flexible cloth material. The shell 12 and the handles 40 are flexible so that the shell 12 can be collapsed to allow the body 26 of the patient 22 to be rolled or otherwise moved into and out of the interior space 28 without discomfort arising from the body 26 being forced against rigid elements. The shell 12 and the handles 40 are also flexible so that the stretcher apparatus 10 may be placed within a compact space such as within a washing machine.

A closure 50 is coupled to the shell 12 for maintaining the top wall 16 of the shell 12 in a closed position 52. The closure 50 comprises at least one zipper 54 but may include snap buttons, hook-and-loop fasteners, a tie, or the like.

A hood 56 is coupled to the shell 12 adjacent to the opening 20 and is configured for at least partially enclosing a head 58 of the patient 22 when the body 26 is contained in the interior space 28. The hood 56 may also comprise the flexible fabric material and an interior insulation layer 38. The hood 56 is detachable from the shell 12 via a connector 60 that is coupled to the hood 56 and the shell 12. The connector 60 releasably couples the hood 56 to the shell 12 and comprises a zipper 62 but may include snap buttons, a hook-and-loop fastener, a tie, or the like.

In use, the top wall 16 is moved with respect to the perimeter wall 18 to form the aperture 64, and the patient 22 is inserted into the interior space 28 through the aperture 64. The top wall 16 is then secured to the perimeter wall 18 in the closed position 52 with the closure 50 to enclose the body 26 of the patient 22 and keep the patient 22 warm and dry. The hood 56 may be attached and the head 58 of the patient 22 placed in the hood 56 to keep the head 58 warm and dry.

With respect to the above description then, it is to be realized that the optimum dimensional relationships for the parts of an embodiment enabled by the disclosure, to include variations in size, materials, shape, form, function and manner of operation, assembly and use, are deemed readily apparent and obvious to one skilled in the art, and all equivalent relationships to those illustrated in the drawings 40 and described in the specification are intended to be encompassed by an embodiment of the disclosure.

Therefore, the foregoing is considered as illustrative only of the principles of the disclosure. Further, since numerous modifications and changes will readily occur to those skilled in the art, it is not desired to limit the disclosure to the exact construction and operation shown and described, and accordingly, all suitable modifications and equivalents may be resorted to, falling within the scope of the disclosure. In this patent document, the word "comprising" is used in its 50 non-limiting sense to mean that items following the word are included, but items not specifically mentioned are not excluded. A reference to an element by the indefinite article "a" does not exclude the possibility that more than one of the element is present, unless the context clearly requires that there be only one of the elements.

I claim:

1. A stretcher apparatus comprising:

a shell enclosing an interior space configured for containing a body of a patient, the shell including a base wall, a top wall, and a perimeter wall being coupled to and extending between the base wall and the top wall, the perimeter wall having an opening extending therethrough configured for receiving a neck of the patient when the body is contained within the interior space, 60 the top wall being movable with respect to the perimeter wall to form an aperture to the interior space, the

shell comprising a flexible fabric material, the perimeter wall including a front end, a rear end, a first lateral side and a second lateral side, the opening being positioned in the front end, wherein the base wall, the perimeter wall, and the top wall each include an interior insulation layer;

a closure being coupled to the shell for maintaining the top wall of the shell in a closed position, the closure extending around a top of the perimeter wall and engaging a peripheral edge of the top wall to the top of the perimeter wall; and

a plurality of handles being coupled to an outer surface of the shell for carrying the shell and the patient, the plurality of handles being distributed around the perimeter wall of the shell.

2. The apparatus of claim 1, wherein the closure comprises at least one zipper.

3. The apparatus of claim 1, further comprising a hood 20 being coupled to the shell adjacent to the opening and being configured for at least partially enclosing a head of the patient when the body is contained in the interior space.

4. The apparatus of claim 3, wherein the hood is detachable from the shell.

5. The apparatus of claim 4, further comprising a connector being coupled to the hood and the shell, the connector releasably coupling the hood to the shell.

6. The apparatus of claim 5, wherein the connector comprises a zipper.

7. The apparatus of claim 1, wherein the flexible fabric material of the shell is water-impermeable.

8. The apparatus of claim 1, wherein each handle of the plurality of handles comprises a flexible cloth material.

9. A stretcher apparatus comprising:

a shell enclosing an interior space configured for containing a body of a patient, the shell including a base wall, a top wall, and a perimeter wall being coupled to and extending between the base wall and the top wall, the perimeter wall having an opening extending therethrough configured for receiving a neck of the patient when the body is contained within the interior space, the top wall being movable with respect to the perimeter wall to form an aperture to the interior space, the shell comprising a flexible fabric material, the perimeter wall including a front end, a rear end, a first lateral side and a second lateral side, the opening being positioned in the front end, wherein the base wall, the perimeter wall, and the top wall each include an interior insulation layer, the flexible fabric material being water-impermeable;

a plurality of handles being coupled to an outer surface of the shell for carrying the shell and the patient, the plurality of handles being distributed around the perimeter wall of the shell, each handle of the plurality of handles comprising a flexible cloth material;

a closure being coupled to the shell for maintaining the top wall of the shell in a closed position, the closure extending around a top of the perimeter wall and engaging a peripheral edge of the top wall to the top of the perimeter wall, the closure comprising at least one zipper;

a hood being coupled to the shell adjacent to the opening and being configured for at least partially enclosing a head of the patient when the body is contained in the interior space, the hood being detachable from the shell; and

a connector being coupled to the hood and the shell, the connector releasably coupling the hood to the shell, the connector comprising a zipper.
